UNITED STATES PATENT OFFICE.

LYMAN P. ARMSTRONG, OF SAN JOSE, CALIFORNIA.

FASTENER.

Application filed November 2, 1925. Serial No. 66,318.

One object of the invention is to provide a fastener for joining the edges of fabrics or any similar flexible material that will not pull off when the fabric is put through a wringer, nor wear through the fabric.

Another object is to provide a fastener that may be applied to the fabric without the use of needle or thread.

Another object is to provide a fastener 10 that grips a relatively large portion of the fabric instead of a few threads as in the case of the ordinary fastener.

Still another object is to provide a fastener that will not become loose except by 15 manually twisting one part relative to the other.

And finally, it is an object to provide a fastener that is simple in form and construction, economical to manufacture and highly 20 efficient in its practical application.

In the drawing:—

Figure 1 is a perspective illustration of the two parts embodying my invention.

Figure 2 is a plan view of a blank form 25 showing how the parts may be cut from sheet material.

Referring more particularly to the drawing, the blank for one part of the fastener is formed of a triangular piece of sheet 30 metal as 1 provided with a "saw-tooth" edge 2. The apex of the triangle, opposite to the teeth 2, is provided with an extension 3 provided with lateral extensions 4—4 and end portion 5.

In forming this part for use the teeth 2 are bent at substantially right angles to the plane of part 1, and the part 3—4—5 is bent in the same direction and at substantially right angles to the plane of part 1 along line 35 6. This end portion is also folded over along line 7 so that edges 8^a and 9^a of parts 4—4 are in alignment, and end portion 5 lies flat against part 3. This formation is clearly shown in Figure 1.

The other part of the fastener is formed 45 of a triangular piece of sheet metal 8 having a "saw-tooth" edge 9 formed along one side, the apex of the triangle opposite to edge 9 terminating in a blunt edge 10.

A rectangular cut 11—12—13 is made in 50 part 8 transversely thereof and adjacent to edge 10, this cut having a width substantially equal to the width of part 3 on fastener part 1. Another cut is made at 14 connecting with cut 13 and extending backwardly therefrom a distance substantially

equal to the total width of part 4—3—4 of part 1, and preferably lying parallel with one side edge of part 8 and adjacent thereto. Another cut 15 is shown connecting with cut 14 adjacent to the rearward end thereof and extending backwardly and angularly therefrom to a point 16.

In forming this part 8 for use, the teeth 9 are bent at substantially right angles 65 thereto as shown and the lip 17 formed by cuts 11—12—13 is bent in the same direction along line 18 as shown. The lips 19—20 formed by cuts 14—15 are bent in the opposite direction and at substantially right 70 angles to the plane of part 8 along lines 21—22 respectively. This part of the fastener when cut and formed as described is clearly shown in Figure 1.

In using the fastener the teeth are thrust 75 through the cloth from one side and flattened up against it from the other side as shown in dotted lines at 23, thereby securing a firm grip on the cloth and securely fastening the parts in position.

To secure one part to the other, one part is twisted slightly relative to the other and the folded end portion 3—4—5 on fastener part 1 inserted through orifice 24 in part 8, the upstanding lips 19—20 guiding the 85 same into position when the fastener is so positioned that it can not be readily seen by the user. When these parts are engaged the natural pull of the cloth will cause the parts 3—4—5 to slide down into their seat 90 in orifice 25 and bearing against lip 17.

The fastening may be readily separated by a reversal of this process, but due to its peculiar formation and interlocking feature this reversal can only be successfully carried out by manual manipulation of the parts.

This fastener is economical to manufacture as it may be readily stamped out of sheet metal with but little waste, the cut 100 forming one set of teeth as 2 also forming the other set 9, and the parts cut to form orifices 24—25 functioning as guides in case of lips 19—20 and as a seat for the hook portion 3—4—5 in the case of lip 17. The triangular formation provides a long edge for fastening to the cloth, and a small angular locking portion.

One of the most important features of 110 this invention is in the formation of the teeth 2 and 9. In this construction the points of the teeth are inclined toward one side

edge and overlap their base portions so as to provide notches wherein the threads of the cloth are bunched when the teeth are thrust through the cloth. Pounding down the teeth curves the tips first and causes the teeth to cross the bunched threads and bind the fastener part securely in position.

By constructing the device as described the two parts are almost identical in form, and 10 the blanks may be cut from sheet metal as shown in Figure 2 with practically no waste.

Orifices 26 are also provided in these parts 1 and 8 adjacent the toothed edges 2 and 9, so that they may be sewed in position if so 15 desired, to avoid having the teeth either seen or felt when they are not placed on a hem or facing.

I claim:—

1. A fastener comprising two relatively 20 thin triangular elements having interlocking devices formed on opposing apices, the edge of each element opposite to its locking apex being sharply serrated, with teeth inclined toward one side edge of the element and 25 turned at an angle to the plane of the fastener.

2. A fastener comprising two relatively 30 thin triangular elements, each element having fastening means formed along one edge thereof, one element having a hook formed on the apex thereof opposite the fastening edge, and the other element having a slot formed in the apex thereof opposite the fastening edge and adapted to receive the said

hook, the said slot having a portion lying 35 substantially parallel with the said fastening edge and a portion lying substantially parallel with one side of said triangular element, the part removed from said first named portion of the slot being bent at 40 right angles to the plane of the element on one side thereof, and the parts removed to form said second named portion being bent at an angle to the plane of the element on the opposite side thereof. 45

3. A fastener comprising two relatively thin triangular elements, each element having fastening means formed along one edge thereof, one element having a hook formed on the apex thereof opposite the fastening 50 edge, and the other element having a slot formed in the apex thereof opposite the fastening edge and adapted to receive the said hook, the said slot having a portion lying 55 substantially parallel with the said fastening edge and a portion lying substantially parallel with one side of said triangular element, the part removed from said first named portion of the slot being bent at an angle to the plane of the element on one side thereof and 60 adjacent to the apex thereof, and the parts removed to form said second named slot portion being bent at an angle to the plane of the element on the opposite side thereof and on the edges remote from the adjacent edge 65 of the element.

LYMAN P. ARMSTRONG.
